Ind., assignors to Globe Valve Corporation,
Delphi, Ind., a corporation

Application December 1, 1941, Serial No. 421,099

13 Claims. (Cl. 4-199)

This invention relates to a combination overflow and pop-up drain suitable for sinks, lavatories, and more particularly bath tubs.

The chief object of this invention is to provide a structure of the aforesaid character, that may be supplied to the plumber substantially completely assembled and which includes no intricate parts and which is provided with a plurality of adjustments so that the plumber in attaching the same to the sanitary fixture (lavatory bowl, sink or tub) may readily effect adjustments to accommodate the invention to the fixture for mechanical connection thereto and by another readily operable adjustment can adjust the lift or travel of the pop-up valve after the drain arrangement has been applied to the sanitary fixture.

The chief feature of the invention consists in providing a unitary arrangement of the aforesaid character that may be readily applied to the sanitary fixture as aforesaid, and following application may be readily adjusted for proper lift of the drain valve.

Another feature of the invention consists in the construction being so associated together with respect to the included parts that should supposedly standard and identical sanitary fixtures vary, as is usually the case, the invention readily can be adjusted to compensate for such variation.

Other objects and features of the invention will appear more fully hereinafter.

The full nature of the invention will be understood more fully from the accompanying drawing and the following description and claims.

In the drawing, Fig. 1 is a central sectional view on an enlarged scale and substantially three fourths actual size.

Fig. 2 is a top plan view of the control lever, its mounting and connection to the actuating handle, the lever being shown in the neutral position and with the handle adjusted to provide the maximum throw or lift for the drain valve.

Fig. 3 is a similar view showing the parts adjusted for minimum throw of the drain valve.

In the drawing 10 indicates the side wall portion of a sanitary fixture, such as a bath tub, or the like, having an overflow drain opening 11 therein. The bottom 12 of the fixture includes the opening 13 which preferably is provided with a lateral enlargement 13a. Seated in the opening 13 is a spud member 14 terminating in the upper flange 15. This spud member has an elongated portion externally threaded as at 16 and the same forms a tubular passage 17.

Extending into the same is one or more stop members 18. These may be formed integral with the spud member. At least one is provided; and the same is to prevent rotation of the valve member, hereinafter described. The upper end of the tubular portion 17 is flared outwardly as at 17a to constitute a seat for the pop-up valve 19.

This pop-up valve 19 is provided with a central tubular stem 20 and extending outwardly therefrom are the radial aligning wings 19a. This prevents cocking of the valve in the tubular drain portion 17 and insures vertical movement of the valve. The tubular stem 20 slidably receives the member 21, the upper end of which is provided with a threaded bore 22 to receive the threaded portion 23 of a screw 24, the latter seating in as well as passing through, the opening 25 in the valve member. Thus, the valve structure includes the valve with its wings and the stem element 21.

An elbow 26 is internally threaded as at 27 and is adapted to be threaded upon the downwardly projecting portion 16 of the spud 14. There is interposed between the base 12 of the sanitary fixture and the elbow the gasket 28. The elbow at its other end is recessed as at 29 to receive one end of a standard horizontal tube 30. The horizontal tube 30 at its other end is receivable by recessed portion 31 of a T-member 32.

The T-member 32 adjacent the bore 31 is externally threaded as at 33 and a union member or nut 34 with the addition of a gasket 35 seals the tube 30 to the T-member. It is to be understood that the T-member may be moved to the left in Fig. 1 relative to the tube 30 and thus provide for accommodation in length or horizontal distance adjustment.

The downwardly directed end of the T-member 32 is suitably connected to the upper end of a waste line 36; hence, whenever the pop-up valve is elevated, the liquid in the sanitary fixture drains downwardly and through the tube 30 and thence through the waste 36 to the usual sewer connection.

The end of the T-member 32 opposite the connection to the waste 36 is internally enlarged as at 37 to receive the lower end of a standard vertical tube 38, the latter being secured in leakproof relation therewith by means of the gasket 39 and the union or nut member 40. It will be apparent that this connection is of axial extensible type so that vertical adjustment is provided for.

The upper end of the tube 38 is seated in the bore 41 of the angular fitting 42, the latter hav-

ing the flange 43 and extending inwardly therefrom and thence forwardly thereof, are a plurality of bosses 44, the same being tapped and threaded as at 45. This flange 43 bears upon a gasket 46 and it in turn bears upon the rear face 5 of the portion 10 of the sanitary fixture about the opening 11 thereof, said opening being the overflow drain.

The overflow plate 47 may be of any suitable design. It, however, is apertured as at 48 and screws 49 are associated with the tapped bores 55 of the bosses 44 and serve to rigidly clamp the overflow plate and the elbow arrangement 42 to the sanitary fixture at the overflow opening 11. Herein the overflow plate is shown provided with the openings 53 for overflow purposes.

Referring more particularly to the central portion of Fig. 1, it will be noted within the tube 33 the T-member 32 and the tube 33 is an angular rod 51. The vertical leg thereof at its upper end is threaded as at 51a. The lower and horizontal leg thereof at its free end is threaded as at 51b. Mounted on the latter is a locknut 52. A horizontal bar member 53 is internally threaded as at 53a and 53b, the latter receiving the threaded end 51b of the angular rod 51 and the adjustment is locked by the nut 52.

A member 54 at one end has pivotal connection as at 55 with the end 21a of the valve stem element 21. The other end of the member 54 is 30 threaded as at 54a and this threaded portion is received by the threaded bore 53a of the horizontal bar member 53 and is locked in the adjusted position by the lock-nut 53.

It will be quite apparent there is a considerable range of horizontal adjustment possible between tube 33 and T-member 32, and there is a similar corresponding range of adjustment possible between the end 51b and the end 54a of the two horizontally aligned members through the horizontal adjusting member of what might be broadly termed turnbuckle type, the member 53a being provided with the opening 57 for control purposes, although the exterior of the horizontal bar 53 may be fashioned for tool engagement.

Adjustably mounted on the threaded end 51a of the vertical portion of the angle rod 51 is the member 58, the latter being bored and internally threaded as at 58a. A lock-nut 59 maintains the threaded members in the adjusted position. The upper end of this member 58 is bifurcated as at 60, and extended across the bifurcations is the pivot member 61. A rod member 62 is reduced at 63 and this reduced tongue portion is seated between the bifurcations 60 and is pivotally connected thereto by means of the pin 64. Rod 51 carries aligner 77.

The member 62 herein is shown apertured as at 64 to receive a cotter key 65 against which bears a washer or bearing plate 66, in turn bearing against one end of a coil spring 67. The other end of this coil spring bears against a washer 68. This washer 68 is limited in its movement axially of the member 62 by means of a shoulder stop 69. The outer and free end of this member 62 is reduced and threaded as at 70.

A handle having the hand engageable portion 71 is provided with a partial ball formation 72 and this is internally threaded as at 73 to receive the threaded end 70 of the member 62. The overflow plate 47 is provided with a circular opening 74 which is slightly smaller than the partial spherical portion 72 of the handle member so

that the handle member cannot be drawn into and through the plate.

The plate adjacent the opening 74 and on opposite sides thereof, is provided with two triangular abutments 75, the same straddling the opening 74, as shown more clearly in Figs. 2 and 3. The two triangular portions 75 have the tips 76.

It will be quite apparent vertical adjustment is possible with respect to the tube 33 and the T-member 32 to position the angle member 42 at a greater or less elevation within the range of the adjustment associated with the T-member.

It will also be apparent that vertical adjustment is possible between the member 58 and the angular member 51 to correspond with the tubular vertical adjustment.

As previously pointed out, standard sanitary fixtures do have some variation in not only the horizontal distance between the openings 11 and 13 but also the vertical distance therebetween. Furthermore, the shape of the wall 19 may vary slightly. Hence, a fixture assembled as herein illustrated, may be readily adapted to such sanitary fixture. Briefly such installation is effected as follows:

The screw 23—24 is first removed. The horizontal bar member 53 is then raised by tripping the level handle 71. The valve or stop 19 then is removed. The drain spud 14—15 then is removed. The angle member 51 is so arranged that it is exactly in the center of the T-member 32 with respect to the horizontal branch 31 thereof. The drain then is attached to the tub in the usual manner and no cutting off is required. The lever handle 71 then is applied until it bears firmly against the overflow plate 47. The overflow plate 47 then is tightened by screwing up on the screws 49. The drain arrangement then is attached to the sanitary fixture. The lever then is actuated and in the event the drain is not closed by the valve 19, when the handle is tipped upwardly, the handle 70 is untightened or backed off, for example, from the position shown in Fig. 3 toward the position shown in Fig. 2. The result of this adjustment is that the length of the leverage between the fulcrum 76 and the pivot 61 is changed and consequently, the vertical travel of the member 21 is correspondingly or proportionally changed.

Tightening up on the handle reduces the throw of the actuating mechanism for the pop-up valve. Loosening the handle member increases the throw. The spring structure 67 disclosed serves to constantly draw the handle into bearing engagement with the overflow plate 47 and normally prevents casual or accidental rotation thereof but permits forcible rotation thereof for throw adjustment purposes.

From the foregoing, therefore, it will be understood that the attachment to the drain may be readily adjusted for the mounting upon and to the requirements of the sanitary fixture; and after having been mounted thereon as described and as illustrated in Fig. 1, the valve control adjustment is effected to obtain proper actuation of the valve so that when the handle is up, the valve is fully seated and closed and when the handle is down, the valve is fully open to permit drainage of the sanitary fixture to the waste 36.

It will be obvious from Fig. 1 that when the parts are positioned as illustrated therein, that the spring 67 pushes downwardly on the angle member 51 and this holds the valve 19 firmly seated in closed position. It will be equally obvious that when the handle 71 is depressed down-

wardly so that the arm 62 extends upwardly, that the spring 67 now functions operatively in the opposite direction, that is, it holds the angle member 51 elevated and hence, it holds the valve 19 wide open. Thus, the valve 19 is either positively held closed or open by the single spring 67.

While the invention has been illustrated and described in great detail in the drawing and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In an overflow and bottom drain mechanism for mounting upon a sanitary element having an overflow opening and a bottom drain opening therein, angularly arranged tubular conduit connections from said openings to a waste line, an overflow passing means mountable in the overflow opening, and a spud and pop-up drain valve mountable in the drain opening, the combination of a rigid angular means for valve control and in the tubular conduit and having its ends terminating therein, one end being juxtaposed relative to the overflow means and the other adjacent the valve, a pivotal connection between the said other end of the angular means, and said valve, and a handle lever pivotally mounted upon the overflow passing means and having a handle portion exposed relative to the conduit and an operating portion concealed by said overflow passing means and within the conduit and pivotally connected to the said one end of the angular control means, said lever being fulcrumed on the overflow passing means for positively opening and closing the valve, the handle lever being of longitudinally extensible character for adjustment of pop-up valve travel.

2. A mechanism as defined by claim 1, characterized by each of the angularly arranged portions of the conduit connections being of longitudinally adjustable character, and independent of the other, and each of the corresponding portions of the included angular control means being similarly adjustable, any major adjustment of a conduit connection requiring angular control means corresponding adjustment to prevent conduit-control means binding and corresponding positive two-way valve actuation.

3. The combination with a sanitary fixture pop-up drain structure including a spud, a tubular member connected to the lower end thereof and with the fixture therebetween, a vertical connection member, a conduit connecting the tubular and vertical connection members, the conduit having telescopic connection with one of said members for spacing adjustment between spud and connection member, a pop-up valve in said spud and having a depending stem with its lower end in juxtaposition to the intersection of the projections of the conduit axis and the spud and longitudinally adjustable means in the conduit manually movable vertically across the same and pivotally connected at one end to the lower end of the valve stem for positive valve movement in opposite direction.

4. In an overflow positionable control for a sanitary fixture having a pop-up drain valve, and an overflow passing means, the combination of an angular control member having one portion included within an overflow riser connected to the passing means and the other portion of said

member being included in the drain from the valve for interior and positive connection to said valve for positive actuation of said valve for opening and closing and by said member, the valve and overflow passing means being laterally offset relative to each other, a lever pivotally mounted on the overflow passing means, and having a manually operable, sanitary fixture exposed handle portion and an overflow passing means concealed portion, and connector means adjustably connected at one end to the upper end of the angular member and pivotally connected at its other end to the concealed lever portion.

5. A control as defined by claim 4, characterized by the lever and overflow passing means pivotal mounting being of adjustable character for varying the effective lever arm length of the lever for the purpose described.

6. In combination with an overflow passing means and a drain riser thereto, a drain valve control including valve actuating means in the riser terminating at its upper end adjacent the passing means, said passing means including an apertured plate, a lever extending through the plate aperture and having an exposed handle portion and a passing means concealed portion, the latter portion having pivotal connection with the upper end of said valve actuating means, the handle and concealed portions being aligned, and an axially adjustable connection therebetween for valve actuating means "throw" adjustment.

7. A structure as defined by claim 6, characterized by the plate aperture being of ball-socket type and the handle having a ball-like formation seatable in said socket, and means on the lever handle normally constraining the ball into socket engagement regardless of lever-handle axial adjustment therebetween.

8. In combination with an overflow passing means and a drain riser thereto, a drain valve control including elongated, relatively rigid valve actuating means in the riser for positive actuation of a drain valve to wide open or fully closed position, said valve actuating means terminating at its upper end in close proximity to the passing means, said passing means including an apertured plate, the plate aperture being of socket type, a lever extending through the plate aperture and having an exposed ball-like formation including handle portion and a passing means concealed portion, the latter portion having pivotal connection with the upper end of said elongated means, an axially adjustable connection between the handle and concealed portions for elongated means "throw" adjustment, the plate socket being outwardly directed, a pair of substantially triangular-like abutments upon the plate and rearwardly directed therefrom, said abutments being spaced apart with the aperture therebetween and having their rearmost portions aligned for single fulcrum formation, a bearing member slidable upon the lever and bearing upon the fulcrum formation, retaining means upon the lever, and constraining means operatively bearing at one end upon the last mentioned means and retained thereby and at the opposite end having operative bearing upon the slidable member to hold the lever and valve actuating means in either of the said positions.

9. In combination with an overflow passing means and a drain riser thereto, a drain valve control including elongated, relatively rigid valve actuating means in the riser for positive actuation of a drain valve to wide open or fully closed position, said valve actuating means terminating

at its upper end in close proximity to the passing means, said passing means including an apertured plate, the plate aperture being of socket type, a lever extending through the plate aperture and having an exposed ball-like formation including handle portion and a passing means concealed portion, the latter portion having pivotal connection with the upper end of said elongated means, an axially adjustable connection between the handle and concealed portions for elongated means "throw" adjustment, the plate socket being outwardly directed, a pair of substantially triangular-like abutments upon the plate and rearwardly directed therefrom, said abutments being spaced apart with the aperture therebetween and having their rearmost portions aligned for single fulcrum formation, a bearing member slidable upon the lever and bearing upon the fulcrum formation, retaining means upon the lever, constraining means operatively bearing at one end upon the last mentioned means and retained thereby and at the opposite end having operative bearing upon the slidable member to hold the lever and valve actuating means in either of the said positions, and stop means on the lever limiting the maximum sliding movement of the slidable member under the influence of the constraining means.

10. A mechanism as defined by claim 1, characterized by the handle lever being pivotally connected to the angular valve control means and having a ball-like formation between its ends, the overflow passing means including an aperture of outwardly directed ball socket character, the longitudinally extensible handle lever including a threaded forwardly extending end of the lever, said end extending through the overflow passing means aperture, the ball formation of the handle lever having a threaded socket for threaded end reception.

11. A control for a sanitary fixture—having a pop-up drain valve, and an overflow passing means, the combination of an angular control member having one rigid portion included within an overflow riser connected at its upper end to

the overflow passing means and another portion rigid with and angular to the former portion and included in the drain from the valve, said another portion of the angular member having pivotal connection to the valve within the drain therefrom for positive two-way actuation of the valve by said member, the valve and overflow passing means being laterally offset relative to each other, a lever pivotally mounted on the overflow passing means and having a manually operable, sanitary fixture exposed handle portion and an overflow passing means concealed portion pivotally connected to the angular shaped, rigid, unitary control member, yielding means constraining said lever, and triangular-like abutment means operatively associated with the overflow passing means and operatively associated with said yielding means whereby the latter holds the pop-up valve in the wide open or fully closed position dependent upon the position of the handle portion.

12. A control of the character defined by claim 11, characterized by the lever being of longitudinal extensible type for valve throw adjustment purposes.

13. In a sanitary fixture structure including a pop-up drain valve, a drain from the bottom of the fixture and controlled by said valve, and an overflow conduit connected at its upper end to the fixture for overflow drain purposes and at its opposite end to the drain, the overflow conduit being offset laterally of the valve associated portion of the drain, the combination of means included with the overflow conduit and valve associated portion of the drain and having at one end direct connection to the valve for the positive opening and closing thereof, and a handle lever having a fixture exposed portion arranged for manual manipulation for valve control, and an overflow concealed portion pivotally connected to the other end of said means for bodily raising and lowering of the same for positively opening and closing said valve respectively.
